COMBINED WASHING AND SCRAPING TOOL FOR PAINT ROLLERS

Alvin E. Seibel, 1528 Roosevelt Drive, Chowchilla, Calif.

Filed June 1, 1964, Ser. No. 80,220

Term of patent 14 years

(Cl. D9—2)

FIG. 1 is a top plan view of a combined washing and scraping tool for paint rollers.

FIG. 2 is a bottom plan view thereof.

FIG. 3 is a side elevational view thereof.

FIG. 4 is a front perspective view thereof.

FIG. 5 is a perspective view thereof.

The opposite side, not shown, is substantially the same in appearance as the side shown.

The broken line showing of the paint roller in FIG. 5 is for illustrative purposes only.

I claim:

The ornamental design for a combined washing and scraping tool for paint rollers, as shown and described.
